SOUND TRANSMISSION REDUCTION STRUCTURES

Filed Oct. 7, 1930

UNITED STATES PATENT OFFICE

ROBERT S. PHILLIPS, OF OAK PARK, ILLINOIS, ASSIGNOR TO AMERICAN HAIR & FELT COMPANY, A CORPORATION OF DELAWARE

SOUND TRANSMISSION REDUCTION STRUCTURES

Application filed October 7, 1930. Serial No. 487,078.

My invention relates to structures for reducing sound transmission of the type comprising masses of fibrous material, such as hair, hair felt, or a combination of different 5 kinds of fibers, arranged heterogeneously and located between sheets of paper or the like.

My objects, generally stated, are to provide a structure of the type above referred 10 to which may be manufactured more economically, be of reduced thickness, with consequent reduction in the amount of material required, and present greater obstruction to sound transmission than structures as hitherto provided.

Referring to the accompanying drawing:

Figure 1 is a broken perspective view of a structure for reducing sound transmission and constituting one of the embodiments of 20 my invention.

Figure 2 is an enlarged, broken, view in vertical sectional elevation of the structure shown in Fig. 1, and

Figure 3 is a broken, perspective, view of 25 a wall construction in which the structure of Figs. 1 and 2 is installed.

The structure shown in Figs. 1 and 2, and in Fig. 3 as installed in a wall construction, and which is in the form of a blanket, and is 30 represented generally at *x*, comprises several layers 5 of paper, or the like coated throughout the areas of their opposite sides, as represented at 6, with a tacky material such as asphalt preferably of such consistency as 35 to remain slightly viscous under the temperature to which the structure is subjected in use. The several layers 5 are spaced apart as shown, and the spaces therebetween filled 40 with masses 7 of fibrous material such as that above referred to, which become adhered to the tacky coating. The masses 7 of fibrous material are each shown as having a core 8 of paper, or the like, coextensive with 45 the areas of the layers 5, but, as shown, spaced therefrom, the core 8 having punched therethrough, by needles, at close intervals, as for example about one-eighth of an inch, and over their entire areas, portion of the 50 fibers forming the masses 7 thereof, thereby

producing what is commonly known as paper-core punched felt.

In Fig. 3 I have shown one of the situations in which the sound-transmission-reducing structure of Figs. 1 and 2 may be used 55 and the preferred way in which it is installed. In this arrangement the sound-transmission-reducing structure is applied between adjacent studding 9 of a wall or partition structure, to the inner sides of the 60 laths 10 at intervals and is engaged by cross-pieces, or slats, 11 located between the studding 9 and forced against the sound-transmission-reducing structure as shown to compress the latter and in such position secured 65 to the studding, the upper one of the slats being shown by dotted lines to permit of the showing of the way the sound-transmission-reducing structure is deformed by this slat when applied as stated. 70

While both paper sheets and masses of fibrous material disassociated with each other, possess the property of reducing sound transmission, the assembling of these elements in layers into a structure disposed 75 normal to the path of sound waves, results in the reduction of sound transmission to a degree greater than the sum of the effectiveness of these materials separately used; and I have availed myself of this condition 80 and provided a structure of relatively inexpensive construction in the provision of the structures as shown.

It is my aim to reduce to as great a degree as possible vibrations in the sheets of 85 paper produced responsive to the action of the sound waves thereon, thereby commensurately reducing sound transmission.

The compressive forces of the fibrous mass thereof against the paper layers act as elastic cushions over the entire area of the paper and thus reduce vibrations in the latter. The damping action just referred to is further augmented in the constructions shown 90 by the provision of the tacky coating of the paper sheets inasmuch as certain of the fibers of the masses thereof and arranged heterogeneously are placed under tensile stresses, exerting tensile forces of heterogeneous spacing and amount on the paper, in 95 100

addition to the compressive forces exerted against the paper and above referred to. The placing of certain of the fibers of the mass thereof under tension as stated results from the mere fact of adherence of the fibers of the mass to the tacky coating. Furthermore, the production of tensile stresses in the fibers producing tensile forces in the paper to damp vibrations may be, and 10 in the constructions shown are, effected by the provision of the paper-core punched felt above referred to, certain of the fibers of which, in being punched through the core, being placed under tension and acting directly upon the paper by the friction contact of the fibers with the paper core at the perforations therein.

It is desirable that the fiber mass or masses, as the case may be, be under relatively great compression for subjecting the paper to relatively great compressive forces exerted against it by those of the fibers which are under compression, as the degree of damping by such forces is dependent on 25 the strength of such forces. In the construction shown in Figs. 1-3 this condition of augmented compression is effected by associating the sound-reducing structure with slats as above explained.

30 It will furthermore be noted that paper coated as stated will not vibrate as freely as uncoated paper and thus its ability to transmit sound is greatly reduced as compared with uncoated paper. The fact that there is an imperforate layer between the layers of 25 felted fibers is important, as the presence of perforations through the layers of paper would provide an air connection between the entrained air in each of the felt layers, and 40 air is a good conductor of sound vibrations.

The sound-transmission-reducing structure, provided as a blanket as stated, may be made either of such dimensions as to cover the area to be provided with the sound-transmission-reducing structure, or in the form 45 of a continuous sheet which may be cut to provide the section of the desired dimensions.

While I have illustrated and described 50 certain particular embodiments of my invention, I do not wish to be understood as intending to limit it thereto, as the same may be variously modified and altered without departing from the spirit of my invention. Furthermore, the structures as shown 55 incorporate therein, in combination, the various features which I regard as novel. However, these features may be separately, or in various combinations, embodied in 60 structures without departing from the spirit of my invention.

What I claim as new, and desire to secure by Letters Patent, is:

1. A sound-transmission-reducing structure comprising a plurality of spaced apart

imperforate sheets of paper, and loosely assembled fibrous bodies located in the spaces between said sheets, the surfaces of said sheets opposed to said fibrous material being coated with a tacky material to which said fibrous material is adhered. 70

2. A sound-transmission-reducing structure comprising a plurality of imperforate essentially unitary sheets of paper each spaced from the adjacent sheets, and loosely assembled fibrous bodies located in the spaces between said sheets, the surfaces of said sheets opposed to said fibrous material being coated with a permanently tacky material to which fibers of said mass are adhered. 80

3. A sound-transmission-reducing structure comprising a plurality of imperforate sheets of paper each spaced from the adjacent sheets, masses of cushioning material filling the spaces between said sheets, 85 said masses each comprising a layer of loosely assembled fibers pricked through a layer of reinforcing paper, the surfaces of said imperforate sheet opposed to said cushioning masses being coated with tacky material 90 to which the fibers of said masses are adhered. 95
